UNITED STATES PATENT OFFICE.

RUSSELL T. KINGSFORD, OF WYNCOTE, PENNSYLVANIA, ASSIGNOR TO ATWATER KENT MANUFACTURING COMPANY, OF PHILADELPHIA, PENNSYLVANIA, A CORPORATION OF PENNSYLVANIA.

LOUD SPEAKER.

Application filed November 3, 1923. Serial No. 672,512.

My invention relates to telephone structure for converting sound-representing current into sound waves, or vice versa, and more particularly, for utilization in connection with horns and like amplifiers utilizable for any purpose, and particularly as so-called "loud speakers" in connection with radio telephonic apparatus.

My invention resides in features of structure, combination and arrangement of parts of the character hereinafter described.

For an illustration of some of the various forms my invention may take, reference is to be had to the accompanying drawings, in 15 which:

Fig. 1 is a vertical sectional view of apparatus embodying my invention.

Fig. 2 is a plan view, partly in section, on the line 2—2 of Fig. 1, with several of the 20 parts, including the diaphragm, removed.

Fig. 3 is a horizontal sectional view, partly in plan, on the line 3—3 of Fig. 1.

Fig. 4 is a plan view of the cap or casing closure.

Fig. 5 is a fragmentary sectional view of the cap with certain of the parts carried thereby.

Fig. 6 is a perspective view of one of the pole pieces.

Fig. 7 is a perspective view of a terminal bracket.

Fig. 8 is a side elevational view, partly in vertical section, of a horn structure and base.

Fig. 9 is a vertical sectional view, partly 35 in side elevation, of a form of my apparatus utilizable in connection with the sound arm of a phonograph.

Fig. 10 is a side elevational view of my apparatus in operative relation with the horn structure of a phonograph.

Referring to the drawings, 1 is the hollow base, as of metal, having the chamber or cavity 2 and the neck 3 provided with the passage 4 extending from the chamber 2 to the upper end 5 of the neck 3. The neck 3 is preferably of reduced diameter, as indicated at 6, extending to the upper end of the neck 3 from the shoulder 7, upon which rests the lower end 8 of the horn 9, which is 45 rotatable about a vertical axis upon the

shoulder 7, the horn passage registering and communicating with the passage 4.

Attached to the lower end of the base 1 is the sheet of felt, cloth or equivalent material 10.

Disposed within the chamber 2 in the base 1 is the support or casing 11, of any suitable material, as metal, such as brass, die cast alloy or the like. The casing 11 has the lugs or ears 12 through which extend the screws 13 for securing the member 11 to the base 1.

The casing closure member or cap 14, of any suitable material, but preferably of molded condensite, bakelite or the like, is threaded into or on to the casing 11 or otherwise 18 suitably adjustably supported or secured to the casing 1. In the example illustrated, the annular flange 15 of the cap 14 is exteriorly threaded and threads into the casing member 11, whereby upon rotation of the cap 14 20 with respect to the casing 11 the cap approaches or recedes from the upper end of the casing 11. Extending outwardly from the flange 15 is the integral annular flange or shoulder 14^a having upon its periphery 25 the serrations 14^b forming a suitably roughened grip for the hand for rotatably adjusting the cap 14 with respect to the casing 11.

Adjacent its center the cap 14 has the recess or depression 16, on opposite sides of which 30 are disposed the raised portions or bosses 17 extending somewhat above the portion or depression 18 joining the recess 16. Screw threaded studs 19 have knurled or roughened heads 20 molded in the bosses 17.

The permanent magnet M has adjacent its poles holes receiving the studs 19, upon which are threaded the nuts 21 to hold the magnet M fixedly in position against the iron or steel pole pieces 22 held fixedly in position by the studs 19 and nuts 21 between the magnet M and the bosses 17. Integral with the pole pieces 22 are the upstanding poles 23. Integral with the cap flange 15 are the bosses or abutments 24, having faces with 40 which engage the circular or curved faces 25 of the pole pieces 22 for accurately and fixedly locating the pole pieces 22 and poles 23.

Upon each of the poles 23 is disposed a 45

Upon each of the poles 23 is disposed a 50

spool or coil support 26, suitably held in place, as by the laterally extending portions 27 at the upper ends of the poles 23 and against similar laterally projecting portions 28 adjacent the junction of the pole pieces 22 and poles 23. On the spools or winding supports 26 are the magnet windings, connected in series with each other, the magnet winding having the terminals 28, 28, preferably in the form of sheet conducting material, each connected to an upstanding terminal bracket 29 having the horizontal arm 30 and the downwardly extending lug 31, struck up from the member 30, and extending into a recess 32 in the cap 14. The threaded studs 33 have the heads 34 molded in the cap 14. Each member 30 has a hole 35 through which a stud 33 extends. Threaded upon each stud 33 is a nut 36, by which the member 30 and bracket 29 are fixedly secured in place on the inside of the cap 14, the lug 31 preventing rotation of and holding the bracket 29 in predetermined fixed position. Between the second nut 37, threaded upon the stud 33, and the nut 36 is held the terminal 38 upon the flexible conducting cord 39, the two cords being formed into a cable 40 extending through a hole in the central boss 14^a on the cap 14, and thence through the insulating bushing 41 threaded into the base 1. The cords 39 at their remote ends are provided with the usual cord tips 42 or other suitable means for connecting the magnet winding in any suitable circuit, as, for example, in the anode circuit of a detector or audio frequency amplifying tube of the audion type, as commonly employed in radio telephone receiving apparatus.

From the foregoing description it is apparent that the magnet system of the telephone is fixedly supported upon a cap or casing closure member forming therewith a unit adjustable longitudinally of the axis of the casing member 11.

At the lower end of the sound passage 4 in the neck 3 the base 1 is preferably recessed or chambered, as indicated at 43.

The magnet poles 23 are preferably symmetrically disposed with respect to the coincident axes of the cap 14, casing 11 and sound passage 4, and extending across and above the poles 23 is the circular diaphragm D, of magnetizable material, as soft iron, which may be plated on either or both surfaces. Preferably, the diaphragm D is slightly cupped or concaved upwardly, as indicated in Fig. 1, whereby the diaphragm is in effect bowed or arched downwardly with its center portion approaching the ends of the magnet poles 23. The outer edge of the diaphragm is confined between the soft rubber washers 44 and 45, the former disposed within the casing 11 and lying against the base 1, and the latter lying be-

tween the diaphragm and the preferably rigid ring 46, of iron or other suitable material, and supported by the resilient member or annular spring 47, preferably waved or circumferentially undulated, as indicated. 70 The spring 47 is in turn supported by the inner end of the flange 15 of the cup 14, whereby, upon rotation of the cap 14, it advances into or withdraws from the casing 11, thereby varying the compression 75 upon the spring 47 and thereby varying the compression exerted by the ring 46 upon the washer 45, diaphragm D and washer 44.

The adjustment of the cap 14 accordingly effects a variation of the distance between 80 the ends of the magnet poles 23 and the diaphragm D, and simultaneously varies the confining force exerted upon the outer edge of the diaphragm D. By employment of either one of or both of the easily compressible washers 44 and 45, as the cap 14 and the magnet system are adjusted toward the diaphragm D, the ring 46 evenly distributes the pressure exerted by spring 47 and the diaphragm D recedes slightly from the ends 90 of the poles 23, due to compression of one or both of the washers 44 and 45, but the movement of the poles 23 toward the diaphragm is greater than the recession of the diaphragm D from the poles, whereby by 95 the adjustment described the magnet poles approach nearer the diaphragm, and by the same adjustment the diaphragm is more firmly held at its periphery or outer edge.

Adjustment of the poles 23 with respect 100 to the diaphragm D is desirable, particularly in radio telephone receiving apparatus, because of the wide range within which the amplitude of the sound-representing current varies. With sound-representing current of 105 large amplitude traversing the magnet winding, the poles 23 are preferably at a greater distance from the diaphragm D than in the case when the amplitude of the sound-representing current is small. Ordinarily, a suitable adjustment is effected by rotating the cap 14 to cause the poles 23 to approach the diaphragm D so closely that the latter will be attracted or snap into contact with the poles 23, whereupon the cap 14 is rotated 110 in opposite direction to withdraw the poles 23 slightly to such position that the diaphragm D is just slightly separated from the ends of the poles 23.

While the apparatus above described in 115 connection with Figs. 1 to 8 inclusive has related more particularly to a loud speaker or amplifier horn unit, similar apparatus may be utilized for application to the sound arm and horn of a phonograph, as indicated in Figs. 9 and 10. As indicated in Fig. 9, the casing 11 is provided with the end wall or closure member 48 secured to or integral with the casing 11 and provided with the short neck 3^a having the sound passage 4^a. 120

As indicated, the neck 3^a is adapted to slip into or connect to the end of the tube or sound arm 49 of a phonograph sound arm or horn system comprising the tube 49 pivotally attached to the hollow chamber 50 communicating with the sound arm or tubular member 51, whose sound passage communicates with the phonograph horn 52.

By the arrangement shown, the casing 10 with its cap 14 and the magnet, diaphragm and other described parts, is attached as a unit to the sound arm or tubular member 49 in place of the usual sound-reproducing structure of a phonograph.

15 In the structures of the character hereinbefore described, the pressure exerted by the spring 47 upon the ring 46 reacts upon the end of the cap flange 15, thereby pressing its threads against the threads on the 20 casing 11, thereby firmly holding the magnet system with nicety and exactitude in the position to which adjusted by rotation of the cap 14. Furthermore, with the magnet system adjusted to predetermined position 25 by adjustment of cap 14, the spring 47 will follow the ring 46 and firmly hold the diaphragm D between the rubber rings 44 and 45 notwithstanding their loss of resiliency or flattening as they deteriorate with age.

30 The diaphragm D, particularly when of soft or Swedish iron, mild steel or other oxidizable or corrodible material, is preferably electro-plated on either or both sides, first with copper and then with zinc, to 35 effect a finish or surface avoiding the need for lacquer, varnish or the like commonly employed to prevent rust or corrosion. Furthermore, the application of paint, lacquer, varnish or the like to a diaphragm to 40 some extent affects its sound-reproducing characteristics, and it is accordingly preferred to use a diaphragm free of paint, varnish, lacquer or the like. The electro-plate is preferably sand-blasted on either or 45 both sides of the diaphragm to remove scale and impart suitable character to the surface.

It is preferred that the convex side of the diaphragm D be presented to the magnet system, as illustrated and above described, 50 because the sound waves reproduced by the diaphragm correspond to greater degree and with greater faithfulness with the sound-representing current traversing the magnet winding, and because the volume of the reproduced sounds is greater, than is the case 55 when the concave side of the diaphragm is presented to the magnet system.

It will be understood that while the concavity of the diaphragm is curvilinear, it 60 may be of other outline, as conical, frusto-conical or the like, or the diaphragm may be in the form of a many-sided pyramid of slight altitude, and having, if desired, a small flat center portion. Where the concavity is of curvilinear outline, it may com-

prise a surface of revolution whose generatrix is an arc of either a circle, an ellipse, or any other suitable flat curve.

In radio telephonic reception the sound-representing current, as appearing in the 70 anode circuit of the detector audion or vacuum tube, or in the anode circuit of an audio frequency amplifier tube, varies in magnitude through a relatively great range and has an average value which is quite 75 high when receiving from any given transmitting station; and when receiving from different transmitting stations, the magnitudes of the sound-representing currents as caused by such transmitting stations are 80 relatively widely different. The concavity of the diaphragm is of advantage under these widely varying conditions of strengths of sound-representing currents, because to produce a given deflection of the diaphragm 85 toward the magnet poles a greater force must be applied thereto by the magnet system than in case the diaphragm is straight or flat. This characteristic does not, however, reduce the total amplitude of the diaphragm's vibration, but in fact increases it, since the force required to deflect the diaphragm in opposite direction or away from the magnet system is less than would be 90 the case with a flat diaphragm. Furthermore, because of the aforesaid increased resistance to deflection in one direction and reduced resistance in the other direction offered by the concave diaphragm, the timbre or quality of a voice- or music-representing current is the more faithfully reproduced, since the higher harmonic components of the sound-representing current, upon which depend the timbre or quality, 95 are able adequately to affect the diaphragm 100 which, because of its resistance to deflection, may approach the magnet poles the closer, and with such close approach nevertheless reproduces the lower frequency components 105 of the sound-representing current of great 110 amplitude without striking the magnet poles.

The concave diaphragm, because of the asymmetry of its resistance to deflection in opposite directions, therefore permits closer approach to the magnet poles, with consequent responsiveness to relatively weak sound-representing currents or relatively weak high frequency components thereof, 115 and yet when the magnet winding is traversed by relatively stronger sound-representing currents the reproduction continues as in the first case to be faithful or without great or substantial distortion. The extent of deflection of the concave diaphragm under the influence of the magnet system more closely approximates proportionality to change in length of air gap, or distance between diaphragm and magnet poles, than in 120 the case of the ordinary or straight dia- 130

phragm. With the concave diaphragm, different degrees of deflection thereof correspond more closely or are more nearly proportional to the different degrees in 5 amplitude of the sound-representing current traversing the magnet winding, and therefore the reproduced sound corresponds more closely, as regards lack of distortion, with the sound-representing current.

10 By way of example merely, it may be stated that when the diaphragm is about two and one-half inches in diameter, and has a thickness of about .012 inch, the extent of concavity is about .015 inch, the diaphragm as such having this concave or cupped conformation before placement in the field of the magnet system, which exerts 15 a pull thereon whose magnitude is varied by the sound-representing current. When the diaphragm is stationary in the magnetic field, as when no fluctuating or sound-representing current is traversing the magnet winding, the air gap between diaphragm and the magnet poles may preferably be of 20 the order of .01 inch, with the magnet poles exerting a pull of seven pounds on the diaphragm, when the cap has been rotated in such direction as to withdraw the magnet system from contact with the diaphragm, 25 as hereinbefore adverted to. A normal pull of upwards of three of four pounds, and preferably of the order of seven pounds, upon the diaphragm with zero current in the magnet winding has been found by me 30 to be of advantage, and this is made possible by recourse to a concave diaphragm which may approach the magnet poles as closely as a flat diaphragm on which may be exerted by the poles only a considerably smaller 35 normal pull.

What I claim is:

1. In apparatus of the character described, the combination with a diaphragm-supporting member, of an annular member of resilient material disposed upon said supporting member, a diaphragm disposed upon said annular member, a member adjustable with respect to said supporting member, and a bowed annular spring disposed between said 5 last named member and said diaphragm.

2. In apparatus of the character described, the combination with a diaphragm-supporting member, of a diaphragm, an annular member of resilient material engaging said 55 diaphragm, a member adjustable on said supporting member, and a bowed annular spring intervening between said last named member and said annular member of resilient material for communicating pressure to 10 said diaphragm through said annular member of resilient material.

3. In apparatus of the character described, the combination with a diaphragm-supporting member, of a diaphragm, an annular member of resilient material engaging said 65

diaphragm, a substantially rigid annular member engaging said annular member of resilient material, a member adjustable on said supporting member, and a bowed annular spring confined between said last named member and said second named annular member.

4. In apparatus of the character described, the combination with a diaphragm-supporting member, of a pair of annular members of resilient material one of which is disposed upon said supporting member, a diaphragm disposed between said annular members, a member adjustable upon said supporting member, and an annular spring confined between said last named member and one of said first named annular members.

5. In apparatus of the character described, the combination with a diaphragm-supporting member, of a pair of annular members of resilient material one of which is disposed upon said supporting member, a diaphragm disposed between said annular members, a substantially rigid annular member disposed upon one of said first named annular members, a member adjustable upon said supporting member, and an annular spring confined between said last named member and said substantially rigid annular member.

6. In apparatus of the character described, the combination with a support, of a diaphragm, resilient means confined between said diaphragm and said support, a magnet system co-acting with said diaphragm, a member carrying said magnet system and adjustable on said support, and an annular spring disposed between said last named member and said diaphragm.

7. In apparatus of the character described, a casing, a diaphragm therein, an annular member of resilient material confined between said casing and said diaphragm, a cap having a flange extending into said casing and having threaded engagement therewith, and an undulated annular spring confined between the end of said flange and said diaphragm.

8. In apparatus of the character described, a casing, a diaphragm therein, an annular member of resilient material confined between said casing and said diaphragm, a second annular member of resilient material on the opposite side of said diaphragm, a cap having a flange extending into said casing and having threaded engagement therewith, and an undulated annular spring confined between the end of said flange and said second annular member of resilient material.

9. In apparatus of the character described, a casing, a diaphragm therein, an annular member of resilient material confined between said casing and said diaphragm, a second annular member of resilient material on the opposite side of said diaphragm, a 120

- substantially rigid annular member next to said second annular member, a cap having a flange extending into said casing and having threaded engagement therewith, and an undulated annular spring confined between the end of said flange and said substantially rigid annular member.
10. In apparatus of the character described the combination with a casing, of a diaphragm therein, resilient supporting means for said diaphragm, a magnet system co-acting with said diaphragm, a cap carrying said magnet system, said cap having a flange extending into said casing and having threaded engagement therewith, and an annular spring confined by the end of said flange and exerting pressure on said resilient supporting means.
11. In apparatus of the character described, the combination with a metallic casing, of a resilient ring on said casing, a diaphragm supported thereby, a magnet system, a cap of molded insulating material carrying said magnet system and rotatably adjustable upon said casing for effecting adjustment of said magnet system with respect to said diaphragm, and an undulated annular spring confined between said cap and said diaphragm.
12. In apparatus of the character described, a metallic casing, a diaphragm supported thereby, a magnet system co-acting with said diaphragm, a cap of molded insulating material, a member molded in said cap, and means detachably securing said magnet system to said member, said cap threaded upon said casing to effect by rotation of the cap adjustment of said magnet system with respect to said diaphragm.
13. In apparatus of the character described, a metallic casing, a diaphragm supported thereby, a magnet system co-acting with said diaphragm, a cap of molded insulating material carrying said magnet system and threaded upon said casing to effect by rotation of the cap adjustment of said magnet system with respect to said diaphragm, and an annular spring engaged by said cap and exerting upon said diaphragm a pressure dependent upon the position of said cap with respect to said casing.
14. In apparatus of the character described, a cap of molded insulating material, a magnet system carried by said cap and comprising a magnet, and a member molded in said cap for detachably securing said magnet system to said cap.
15. In apparatus of the character described, a cap of molded insulating material, a magnet system carried thereby comprising a magnet, a member molded in said cap, and means engaging said member and said magnet for detachably holding said magnet system to said cap.
16. In apparatus of the character described, the combination with a cap of molded insulating material, of a magnet system carried thereby comprising a magnet, a stud molded in said cap and extending through said magnet, and means engaging said stud for detachably holding said magnet to said cap.
17. In apparatus of the character described, the combination with a cap of molded insulating material, of a magnet system comprising a magnet and pole piece structure, and a member molded in said cap and detachably securing said magnet and pole piece structure to each other and to said cap.
18. In apparatus of the character described, the combination with a cap of molded insulating material, of a detachable magnet system carried by said cap and comprising a magnet and pole piece structure having registering apertures, said pole piece structure disposed between said magnet and a wall of said cap, and means molded in said cap and extending into said apertures for detachably securing said magnet and pole piece structure to each other and to said cap.
19. In apparatus of the character described, the combination with a cap of molded insulating material, of a detachable magnet system carried by said cap and comprising a pole piece, means for securing said pole piece to said cap, and a boss integral with said cap adjacent which said pole is disposed.
20. In apparatus of the character described, the combination with a cap of molded insulating material, of a magnet system comprising a pole piece having an aperture, means extending through said aperture for holding said pole piece to said cap, and a boss integral with said cap disposed adjacent said pole piece.
21. In apparatus of the character described, the combination with a cap of molded insulating material, of a magnet winding carried by said cap, and means for effecting connection with said winding comprising a terminal bracket having an arm lying against a wall of said cap and an upstanding member, means for securing said arm to said cap, and a connection from said upstanding member to said winding.
22. In apparatus of the character described, the combination with a cap of molded insulating material, of a magnet winding carried by said cap, and means for effecting connection with said winding comprising a terminal bracket, means for securing said bracket to said cap, a connection from said bracket to said winding, said cap having a recess adjacent said bracket, and a lug on said bracket extending into said recess.
23. In apparatus of the character described, the combination with a cap of mold-

- ed insulating material, of a magnet winding carried by said cap, and means for effecting connection with said winding comprising a terminal bracket, a stud molded in said 6 cap and extending through a perforation in said bracket, a connection from said bracket to said winding, said cap having a recess adjacent said stud, and a lug on said bracket extending into said recess.
- 10 24. In apparatus of the character described, a casing, a diaphragm therein, a cap having a flange extending into said casing and having threaded engagement therewith, an annular member of resilient material disposed between said diaphragm and said flange, and an undulated annular spring engaged by said flange and transmitting pressure to said diaphragm through said annular member of resilient material.
- 15 25. In apparatus of the character described, the combination with a concavo-convex diaphragm, of a magnet system comprising a permanent magnet system spaced by air gap from and disposed on the convex side 25 thereof and normally exerting a pull thereon of magnitude upwards of three pounds.
- 20 26. In apparatus of the character described, the combination with a concavo-convex diaphragm, of a magnet system comprising a permanent magnet system spaced by air gap from and disposed on the convex side thereof and normally exerting a pull thereon of magnitude of the order of seven pounds.
- 25 27. A telephone diaphragm which of itself is normally concavo-convex to an extent of the order of the thickness of the diaphragm.
- 30 28. A telephone diaphragm of substantially uniform thickness and which of itself is normally concavo-convex to an extent of the order of thickness of the diaphragm.
- 35 29. Telephonic apparatus comprising a diaphragm which is of itself concavo-convex to an extent of the order of magnitude of the thickness of said diaphragm, and a magnet system comprising a permanent magnet and a winding therefor disposed upon one side of said diaphragm.
- 40 30. Telephonic apparatus comprising a diaphragm which is of itself concavo-convex to an extent of the order of magnitude of the thickness of said diaphragm, and a magnet system comprising a permanent magnet and a winding therefor disposed on the convex side of said diaphragm.
- 45 31. Telephonic apparatus comprising a diaphragm which of itself is concavo-convex to an extent of the order of its thickness, resilient means supporting said diaphragm adjacent its periphery, and a magnet system disposed on one side of said diaphragm.
- 50 32. In apparatus of the character described, the combination with a diaphragm, of members on opposite sides thereof and confining said diaphragm substantially throughout its entire circumference on both sides thereof, a member adjustable toward and away from said diaphragm, and a bowed annular spring disposed between said diaphragm and said adjustable member.
- 55 33. In apparatus of the character described, the combination with a diaphragm-supporting member, of an annular member of resilient material disposed upon said supporting member, a diaphragm disposed upon said annular member, a second member of resilient material on the opposite side of said diaphragm and engaging the same substantially throughout its entire circumference, a member adjustable with respect to said supporting member, and a bowed annular spring disposed between said last named member and said diaphragm.
- 60 34. In apparatus of the character described, the combination with a diaphragm-supporting member, of an annular member of resilient material disposed upon said supporting member, a diaphragm disposed upon said annular member, a second member of resilient material on the opposite side of said diaphragm and engaging the same substantially throughout its entire circumference, a substantially rigid annular member engaging said second member of resilient material, a member adjustable with respect to said supporting member, and a bowed annular spring disposed between said substantially rigid annular member and said member adjustable with respect to said supporting member.
- 65 35. In apparatus of the character described, a metallic casing, a diaphragm supported therein, a magnet system, a cap of moulded insulating material carrying said magnet system, an exteriorly threaded flange on said cap engaging in said casing, and an integral annular flange on said cap extending radially outwardly across the end of said casing for effecting a manual grip for rotatable adjustment of said cap with respect to said casing.
- 70 36. Telephonic apparatus comprising a diaphragm which of itself is concavo-convex to an extent of the order of its thickness, resilient means supporting said diaphragm adjacent its periphery on one side of said diaphragm, and a magnet system disposed on said side of said diaphragm.
- 75 37. In apparatus of the character described, the combination with two diaphragm-confining members, of a diaphragm disposed between them, a member of resilient material disposed between said diaphragm and one of said members, and a bowed spring member disposed between said one of said members and said member of resilient material.
- 80 38. In apparatus of the character described, the combination with two diaphragm-confining members, of a diaphragm disposed between them, resilient material dis-

posed on opposite sides of said diaphragm between said diaphragm and said members, and a bowed spring disposed on one side of said diaphragm between one of said members and the resilient material on the same side of said diaphragm.

39. In apparatus of the character described, the combination with two diaphragm-confining members, of a diaphragm disposed between them, a member of resilient material disposed between said diaphragm and one of said members, a bowed spring member disposed between said one of said members and said member of resilient material, a magnet system on one side of said diaphragm, and means for adjusting said magnet system with respect to said diaphragm.

40. In telephonic apparatus of the character described, the combination with two diaphragm-confining members, of a diaphragm disposed between said members, re-

silient material disposed between the periphery of said diaphragm and one of said members, and a plurality of spring contacts disposed between the other of said members and said diaphragm for transmitting pressure to the periphery thereof at a series of circumferentially spaced regions.

41. In telephonic apparatus of the character described, the combination with two diaphragm-confining members, of a diaphragm disposed between said members, resilient material disposed between the periphery of said diaphragm and one of said members, and an undulatory annular spring disposed between the other of said members and said diaphragm for transmitting pressure to the periphery thereof at a series of circumferentially spaced regions.

In testimony whereof I have hereunto affixed my signature this 1st day of November, 1923.

RUSSELL T. KINGSFORD.
